Julien Stranders

By Paul P. Gelpi

ATTORNEY

UNITED STATES PATENT OFFICE.

JULIEN STRANDERS, OF BROOKLYN, NEW YORK, ASSIGNOR TO HARRY B. KRUGER, OF NEW YORK, N. Y.

ADVERTISING OR DISPLAY DEVICE.

1,313,351.

Specification of Letters Patent. Patented Aug. 19, 1919.

Application filed April 16, 1918. Serial No. 228,907.

To all whom it may concern:

Be it known that I, JULIEN STRANDERS, a subject of the King of England, and a resident of Brooklyn, county of Kings, in the State of New York, have invented certain new and useful Improvements in Advertising or Display Devices, of which the following is a specification.

The present invention relates to improvements in advertising or display devices, and particularly that class of display devices with which the article to be displayed is exhibited in such relation thereto that it supports the display device in display position. An object of the invention is to provide such a device which may be combined with the article to be displayed in a manner as to be attractive and to effectively display the same. More particularly I propose in the present embodiment of my invention to provide a device having a plurality of display panels offset from each other in display position, to the end that a background display panel may be provided behind the article to be displayed and a foreground may be provided before the article to be displayed. A further object is to provide such a device which may be conveniently formed by means of a single operation by means of a stamping die from a sheet of material, preferably cardboard, and which in the non-display position will be flat, so that the device may be conveniently shipped in large quantities and stored without taking up any great amount of room. Another object is to eliminate waste in the manufacture. The various portions of the device fit into each other in the flat or non-display position so that there are no openings left and are so designed that in the display position the attractive appearance of the device will not be sacrificed by the economy in material.

It is also proposed in the present embodiment of the invention to enable the article to be displayed to be first placed in position independently of the display device and thereupon place the device in display relation therewith.

With these and other objects in view an embodiment of my invention is disclosed in the accompanying drawings and this embodiment will be hereafter more fully described with reference thereto and the invention will be pointed out in the claims.

In the accompanying drawings, 55 Figure 1 is a perspective view showing one embodiment of my invention in display position and combined with an article to be displayed. Fig. 2 is a plan view of the device in the flat or non-display position as it 60 is blanked out. Fig. 3 is an end view in display position, and Fig. 4 is a vertical sectional view taken along the line 4—4 of Fig. 1.

Similar reference characters indicate corresponding parts throughout the several figures of the drawings.

Referring to the drawings, the display device formed according to the present embodiment of my invention consists of a rear 70 display panel 10, a front display panel 11 and connecting portions 12 and 13 hingedly connected by score lines respectively to the lower edge of the panel 10 and to the upper edge of the panel 11. The portions 12 and 75 13 are separated by an opening 14, an extension 15 of the panel 10 projecting into the said opening, and adapted, as hereinafter pointed out, to form a supporting leg for the panel 10. An extension 16 of the panel 80 11 also extends into opening portion 14 and is separated from the extension 15 by a cut 17.

The portions 12 and 13 are spaced from the ends of the panel 10 and the upright 85 extensions 18 and 19 of the panel 11 extend at the sides thereof in the flat position of the device, the upper edges of the said portions extending to the lower edge of the upper panel 10, while the inner side edges 90 thereof and the outer side edges of the portions 12 and 13 conform.

While the shape of the panels is arbitrary and may be adapted to any suitable design or plan of decoration, it will be seen that 95 the construction above described enables the device to be manufactured conveniently from very simple dies and there is no waste of material whatever. It will be understood that this same idea may be carried out 100 where the portions 18 and 19 are of a different shape by suitably cutting the material at 20, as the conforming shape of the panel 10 and portions 12 and 13 at this portion of the device do not essentially constitute a decorative portion of the device in the display position.

In the display position of the device the

article to be displayed, as for instance, a container 21, is placed within the opening 14, the panels 10 and 11 having previously been placed in offset relation with each other, 5 the portions 12 and 13 extending laterally between the same. The article engages the supporting leg 15 and a portion of the panel 10 above the same and also engages the intermediate portion of the panel 11 at its 10 inner side, and in this manner the device is rigidly supported. The supporting leg 15 is preferably of a height greater than those portions of the panel 11 connected to the portions 12 and 13, so that in the display 15 position the said portions 12 and 13 are inclined downwardly from the panel 10 and suitable advertising matter may be printed thereon, by reason of this inclination same may be conveniently read by anyone viewing 20 the device. Also advertising matter may be printed upon the panels 10 and 11.

I have illustrated and described preferred and satisfactory embodiments of my invention, but it is obvious that changes may be 25 made therein within the spirit and scope thereof as you will find in the appended claims.

I claim:

1. A collapsible display device comprising 30 spaced display panels and relatively movable means connecting said panels to each other, said device being adjustable to collapsed or erect position with all parts thereof in the same connected relation in 35 both positions of the device, the device having an opening between the panels adapted to receive an article to be displayed, the article engaging the spaced panels to prevent their movement toward each other to collapsed positions, said panels and the connecting means extending in a common plane when the device is collapsed.

2. An advertising device for displaying 45 packages, comprising a pair of display panels, means hingedly connected to said panels and adapted to space the same with relation to each other, said device being provided with an opening extending between said 50 panels, said opening adapted to receive a package to be displayed, said package adapted to engage the front face of one of said panels and the rear side of the other of

said panels to support the panels in display position.

3. An advertising device for displaying 55 packages formed from a single piece of flat material and comprising a front display panel, a rear display panel, means hingedly connecting the panels to each other, said device being provided with an opening extending between said panels, and a supporting leg on said rear panel adapted to extend into said opening in the flat or non-display position of said device, said opening adapted 60 to receive a package to be displayed, the package adapted to engage said supporting leg and the front face of said rear display panel and the rear side of said front display panel to support the same in display position. 70

4. An advertising device for displaying packages formed from a single piece of flat material and comprising a front display panel, a rear display panel, means connecting 75 said panels and hinged respectively to the lower edge of said rear display panel and the upper edge of said front display panel, said device being provided with an opening extending between said panels, said opening adapted to receive a package to be 80 displayed, said package adapted to coöperate with said device to support the same in display position. 80

5. An advertising device for displaying 85 packages formed from a single piece of flat material and comprising a front display panel, a rear display panel, means connecting said panels and hinged respectively to the lower edge of said rear display panel and the upper edge of said front display panel, said device being provided with an opening extending between said panels, said opening adapted to receive a package to be 90 displayed, said package adapted to coöperate with said device to support the same in 95 display position, said front panel having upstanding display portions adapted to extend in the plane of said rear panel and said connecting means in the flat or non-display position of said device. 100

In testimony that I claim the foregoing as my invention, I have signed my name.

JULIEN STRANDERS.
